UNITED STATES PATENT OFFICE.

GEORGE F. WELLS, OF SAN FRANCISCO, ASSIGNOR OF ONE-HALF TO
MANLEY C. LAWTON, OF STATEN ISLAND, CALIFORNIA.

MECHANICAL MUSICAL INSTRUMENT.

SPECIFICATION forming part of Letters Patent No. 393,456, dated November 27, 1883.

Application filed July 24, 1883. Serial No. 250,929. (No model.)

To all whom it may concern:

Be it known that I, GEORGE F. WELLS, of San Francisco, San Francisco county, State of California, have invented an Improvement in 5 Automatic Musical Instruments and Motors Therefor; and I hereby declare the following to be a full, clear, and exact description of the same.

My invention relates to that class of musical instruments in which a strip of suitable perforated paper is caused to travel over the apertures in the range, said instruments being of the general organ type and known under the general name of "automatic;" and my invention relates especially to a power apparatus or motor for effecting the travel of the perforated music-paper, its proper government, and its rewinding.

The main object of my invention is to provide a motor for this class of instruments of such a nature and so operated that without interference with the main functions of the pedals—namely, that of operating the bellows—it shall transmit its power to effect the travel of the music-paper, permit variation of its rate of speed, and allow for its proper government and control, so as to give a variation of time to the music, according to the will and taste of the performer. Other objects are to provide a simple motor, easily constructed and operated, and a means for rapidly rewinding the music-roll.

My invention consists, broadly and essentially, in the combination, with power-transmitting mechanism by which the travel of the music-paper is effected, of a motor of suitable construction, whose operation is effected by springs, the power of which is instituted and controlled by connections direct or indirect 40 with the pedals.

My invention further consists, in connection with a motor thus connected and operated and power-transmitting mechanism to the music-roll, of a suitable speed-regulator interposed 45 in the power mechanism, whereby the speed of the motor may be varied independently of the stroke of the pedals and of the consequent power transmitted to the bellows of the instrument.

My invention also consists in the peculiar

and novel construction of the motor, its arrangement in connection with the pedals, the arrangement of the power-transmitting mechanism, and the construction and arrangement of the rewinding mechanism, all of which I shall hereinafter fully describe by reference to the accompanying drawings, in which—

Figure 1 is an elevation showing the case of the automatic instrument, (its front being removed,) and the arrangement of the several parts within it. Fig. 2 is a vertical cross-section of the instrument, showing the motor in side elevation. Fig. 3 is a detail showing the motor-connection direct with the pedal. Fig. 4 is a plan looking down on the music-paper passing over the range. Fig. 5 is a detail view of the clutch-piece, showing the engagement of its jaw with the flange *h* of the wheel *H*.

A is the case of the instrument.

B is the music roll holder, on which is wound a strip of perforated music-paper, *b*, and C is the drum or roller with which the end of the music-paper is connected, and upon which it is wound as it is drawn off the holder B, said paper passing over the usual apertures in the range D.

E are the feed-boards of the bellows of the instrument, and F are the pedals, which are connected by the usual straps, *f*, with the feed-boards, whereby said boards are moved forward as the pedals are pressed down, said boards moving back under the influence of the springs *e*, all in the usual manner.

G is a bracket hanging within the frame of the machine from the floor of the wind-chest *a*, and having journaled in its lower end the motor-wheel *H*, said wheel having on each side, near its rim, a flange *h*. Pivoted within the bracket G, on the same center as that on which the wheel rotates, and on each side of the wheel, is an arm, I, to the end of which is pivoted or jointed at *i* a clutch-piece, J, the inner surface of which, near its end, is provided with a grooved jaw, *j*, which is adapted to fit over the flange *h* of the wheel *H*. The arm I is provided or formed with the extension K, through which passes a screw, *k*, the lower end of which lies just above the clutch-piece J. Said arm I, behind its pivotal cen-

ter, is provided or formed with a lever, L, the upper end of which preferably carries a small anti-friction roll, l, which lies directly in front of the feed board E of the bellows of the instrument. Springs M are attached at their lower ends to the arms I and to the fixed bracket G at their upper ends.

The operation of this clutch is as follows: As the pedal moves down, and through the strap f draws the feed-board E forward, said board comes in contact with the roller l on the lever L, thereby throwing the said lever upwardly and moving the arm I, with its clutch-piece J, downwardly. This movement of the clutch-piece takes place freely, its jaw j slipping on the flange h of the motor-wheel without engaging it, because the arm and its clutch-piece are then extended to their full length or radius, which is so adjusted that its movement shall take place freely, as mentioned. This movement downward of the arm I extends the spring M. As soon as the pedal is relieved and the feed-board E relieves the lever L the spring M pulls up on the arm I, which causes the clutch-piece J to move on its joint i, thereby attempting to shorten the radius, which attempt results in the frictional engagement of its jaw with the flange h on the wheel and causes the partial rotation of said wheel. This rotation continues until the spring M ceases to pull the arm I up; but the clutch-piece J, being carried a little farther by the wheel, comes in contact with the screw k of the extension K above, which causes the disengagement of said piece, throwing it again to the full radius, and thereby freeing the wheel. A similar operation takes place through the opposite pedal and the clutch-arm on the other side, so that the wheel H is given a practically continuous rotation. From the wheel H extends an endless belt, n, to a pulley, N, on a shaft, O, the end of which carries a pulley, o, from which an endless belt, o', extends to the pulley p on the shaft P. On this shaft is a pinion, p', which meshes with the gear e on the winding-drum C. Thus the power of the motor is transmitted to said drum to wind up the music-paper and draw it across the range. Now it will be seen that the power of the motor is not directly developed by its connection with the pedals, but by the springs M. The pedals acting upon the clutch-arms only leave the motor-wheel free; but in thus affecting said arms the power of the springs is developed. By thus applying the power instead of direct from the pedals or the feed-boards an opportunity is afforded for varying and controlling the transmission of power from the motor without in the least affecting the full primary function of the pedals—namely, that of operating the bellows. If the motor were so arranged that its wheel H were rotated by the direct movement of the pedals or the feed-boards E, it is obvious that any attempt to vary the speed of the motor would result in a variation of the power applied to the bellows. This is not desirable. On the contrary, the end to be reached

is to separate the two functions of the pedals in such a manner that the power transmitted to the music-paper can be varied and controlled to give a variation of time to the music at the same time that the full power of the pedals may be transmitted to the bellows in order to maintain the volume of wind and consequent sound. By the arrangement of motor which I have hereshown the result is perfectly accomplished, for the connection of the clutch-arms with the feed-boards or with the pedals is a loose one, and adapted in the first instance to develop only such power of the springs M as may be needed for the greatest speed of the motor. Then by checking the motor by any suitable regulator or governor the speed of the music-paper may be properly varied, and this check on the motor does not interfere with the main function of the pedals, nor does it interfere with the perfect operation of the motor itself, which is of such a character that it works satisfactorily whether the wheel H be engaged by a longer or shorter stroke of the clutch-arms.

One form of speed-regulator I have here shown and will now describe. On the other end of the shaft P is a pulley, p², from which a belt, p³, extends to the pulley q on the shaft q', which carries the fly-wheel Q. The shaft q' has a crank, q², which is connected with a small bellows-governor, R. The details of this governor I need not herein describe, as it formed the subject-matter of my application for patent, Serial No. 273,720, filed May 12, 1888, said governor, however, standing for and representing any suitable form of speed-regulator. This governor carries a brake-block, r, which is adapted to work up against the fly-wheel Q, and as the speed of the motor tends to increase, the brake-block comes in contact with the fly-wheel and checks it, and vice versa, the governor being regulated by the sliding valve r'. Now it will be seen that by so regulating the governor by means of its valve as to permit a certain rate of speed a check is imposed upon the movement of the motor-wheel H below; but this check does not affect the other function of the pedals—namely, that of operating the bellows—for the full stroke may be still imparted to the bellows and a smaller stroke applied to the clutch mechanism, which, however, operates as perfectly as when a greater stroke was applied to it; and so by regulating the governor to another point the motor is affected without affecting the bellows, and it will thus be seen that the full power of the bellows may be maintained, while the travel of the music-paper may be varied at the will of the operator, thus giving a variation of time to the music.

In Fig. 3 I show the motor as being directly connected with the pedal by means of a flexible connecting-strap, S, joining the pedal with the extension K of the arm I. When this is used, the lever L may be omitted, and it will readily be seen that the same operation as heretofore described takes place. By placing the motor between or just in front of the feed-

boards E and down near the pedals I find it best, in order to avoid an inconvenient arrangement of the power-transmitting devices and a consequent waste of power, to carry the belt n directly through the wind chest a. This I do by placing within the chest a two hollow posts, a', and running the belt n through said posts. I am thus enabled to reach the work above in the shortest space.

10 In order to rewind the music paper upon holder B from drum C, I have the following: Upon the shaft P is fixed the pin T, and also mounted upon the said shaft loosely, so that it may slide longitudinally, is a pulley, U, having in its side next to the fixed pin a groove or notch, u, which, when the pulley is forced over, engages said pin, thereby connecting it with the shaft P. The pulley U is operated by a bell-crank lever, V, connected with the stop v, and from said pulley extends an endless belt, u', to a pulley, W, upon the axis of the holder B. When the pulley U is thrown into engagement with the shaft P, so as to communicate rotation in a reverse direction to the holder B, the pinion p', which engages the gear c of the drum C, must be thrown out of engagement with said gear, so as to free the shaft from it, and for this purpose I have the following: The shaft P is so mounted at its pinion end as to have a slight backward and forward movement, sufficient to carry its pinion into and out of engagement with the gear c. This is done by carrying the shaft in a short arm, x, of a bell-crank lever, X, which is pivoted at x'. Its long or horizontal arm x² extends forwardly, and is curved downwardly over a roller, Y, which is on the end of a long pivoted lever, y, engaged by a finger, v', extending downwardly from the stop v. Now, 40 by pulling out said stop the first effect is to turn the bell-crank lever X so as to move the shaft P back and carry its pinion out of engagement, and its next effect is to throw the rewinding mechanism into operation, as here- 45 tofore described.

Having thus described my invention, what I claim as new, and desire to secure by Letters Patent, is—

1. In an automatic musical instrument, and in combination with its pedals and its winding-drum for receiving the music-paper, a motor comprising a rotary wheel and vibrating clutches, a spring for operating said motor, a connection with the pedals for developing the power of the spring, and power-transmitting connections between said motor and winding-drum, substantially as herein described.

2. In an automatic musical instrument, and in combination with its pedals and its winding-drum for receiving the music-paper, a spring-actuated motor having vibrating clutches, a loose connection with the pedals for developing the power of the spring without interference with the primary function of said pedals, and power-transmitting connections between said motor and winding-drum, substantially as herein described.

3. In an automatic musical instrument, and in combination with its pedals and its winding-drum for receiving the music-paper, a motor comprising a rotary wheel and vibrating clutches, a spring for operating it, a loose connection with the pedals for developing the power of the spring without interference with the primary function of said pedals, power-transmitting connections between the motor and the winding-drum, and a speed-regulator for governing the motor, substantially as herein described.

4. In an automatic musical instrument, and in combination with its pedals and its winding-drum for receiving the music-paper, a motor comprising a rotary wheel and vibrating clutches engaging the wheel, springs for operating the clutches to rotate the wheel, connections with the pedals for returning them and developing the power of the springs, and connections from the motor-wheel to the winding-drum, substantially as herein described.

5. In an automatic musical instrument, and in combination with its pedals and its winding-drum for receiving the music-paper, a motor comprising a rotary wheel and vibrating clutches engaging it, springs for operating the clutches to rotate the wheel, connections with the pedals for returning them and developing the power of the springs, power mechanism from said wheel to the winding-drum, and a speed-regulator let into said power mechanism, substantially as herein described.

6. In an automatic musical instrument, and in combination with its pedals, its bellows feed-boards connected therewith, and its winding-drum for receiving the music-paper, a motor comprising a rotary wheel, vibrating clutches engaging the wheel, springs for operating the clutches to rotate the wheel, a contact-connection between the bellows feed-boards and the clutches for returning them and developing the power of the springs, and power-transmitting mechanism between said wheel and the winding-drum, substantially as herein described.

7. In an automatic musical instrument, the vibrating pedals and the bellows feed-boards connected therewith, in combination with the rotary wheel having side flanges, the pivoted arms having clutch-pieces jointed thereto, with jaws for engaging the flanges of the wheel and extensions with set-screws for releasing the clutch-pieces, levers L, extending from the arms and operated by the bellows feed-boards, and springs M, connected with the arms for drawing them up and turning the wheel, substantially as herein described.

8. In an automatic musical instrument, and in combination with the music-paper holder and the winding-drum, on which the paper is received, means for rewinding the paper upon the holder, consisting of the fixed pin on the power-shaft, the grooved sliding pulley on said shaft, adapted to engage the pin, the lever V and the stop v, for moving the sliding pulley, the pulley on the paper-holder axis, and the

endless belt connecting the sliding pulley with the holder-pulley, substantially as herein described.

9. In an automatic musical instrument, the
5 music-paper holder, the winding-drum C, having
the gear c , and the movable power-shaft
P, having the pinion p' , adapted to be thrown
into or out of engagement with the gear on the
10 winding-drum, in combination with the bell-
crank lever X, roller Y, lever y and stop v , for
effecting the disengagement of the pinion and
gear, and the rewinding mechanism consist-
ing of a fixed pin on the power-shaft, the
15 grooved loose pulley U, adapted to engage said
pin, the lever V and stop v , for operating the
sliding pulley, the pulley W on the paper-
holder, and the endless belt between the two
pulleys, substantially as herein described.

10. In an automatic musical instrument, the
wind-chest, the winding-drum above the wind-
chest for receiving the music-paper, and a
motor below the wind-chest for operating the
winding-drum, in combination with the end-
less belt n of the power-transmitting connec-
tions between the motor and the winding-
drum, and the hollow posts in the wind-chest
for leading the endless belt through it, sub-
stantially as herein described. 20 25

In witness whereof I have hereunto set my
hand.
